187,750

LUMINAIRE

Donald E. Husby, Fairview Park, Edmund L. Izzi, North Olmsted, and Clem W. Eberhart, Avon Lake, Ohio, assignors to Westinghouse Electric Corporation, East Pittsburgh, Pa., a corporation of Pennsylvania

Application November 13, 1958, Serial No. 53,369

Term of patent 14 years

(Cl. D48—31)

Fig. 1.

Fig. 2.

Fig. 3.

Fig. 4.

Fig. 5.

Fig. 6.

Fig. 7.

Fig. 8.

Fig. 1 is a top plan view of a luminaire showing our new design;

Fig. 2 is a side elevational view thereof;

Fig. 3 is an elevational view thereof as seen from the right of Fig. 2;

Fig. 4 is an elevational view thereof as seen from the left of Fig. 2;

Fig. 5 is a top plan view of a modified form of the luminaire shown in Fig. 1;

Fig. 6 is a side elevational view of the modified luminaire;

Fig. 7 is an elevational view of the modified luminaire as seen from the right of Fig. 6; and

Fig. 8 is an elevational view of the modified luminaire as seen from the left of Fig. 6.

The dominant features of the luminaire design are shown by solid lines.

We claim:

The ornamental design for a luminaire, substantially as shown and described.
